UNITED STATES PATENT OFFICE

FREDERICK CHARLES SCHUELER, OF GREEN BAY, WISCONSIN, ASSIGNOR TO HUDSON-SHARP MACHINE COMPANY, OF GREEN BAY, WISCONSIN, A CORPORATION OF WISCONSIN

LABELING MACHINE FOR TOILET ROLLS AND THE LIKE

Application filed June 28, 1930. Serial No. 464,482.

This invention relates to improvements in labeling machines for toilet rolls and the like.

It will be understood that in a re-winding apparatus such as that disclosed in a companion application filed by me a web of paper is longitudinally slit and automatically wound upon a set of cores to provide a series of toilet rolls equal in their combined length to the width of the original web. Upon the completion of the re-winding operation whereby these rolls are formed, the operator removes from the re-winding machine a complete set of rolls and substitutes in the re-winding machine a core shaft bearing merely empty cores.

It is the function of the present apparatus to receive the full core shaft and supply a core shaft having the necessary number of empty cores. Between the point at which the full rolls are received and the point where the empty cores are delivered, each core shaft follows a circuitous path across labeling apparatus which automatically applies labels to each roll. Thereupon the core shaft is freed automatically at one end and the full, labeled rolls are automatically stripped therefrom. While the end of the empty core shaft is still free a girl slips empty cores onto the free end of the shaft until the shaft is filled with cores in readiness for a subsequent re-winding operation. Thereafter the free end of the core shaft is again engaged by the conveyor which restores the core shaft to the starting point from which the operator takes it for a subsequent operation of the re-winding machine as above explained.

In the light of the foregoing brief description of the operation of a machine embodying this invention I may say that one of the principal objects of the invention is to provide an automatic labeling machine in which a core shaft may be supported with one end free and the wound and labeled rolls automatically stripped therefrom and new cores placed thereon.

It is a further very important object of the invention to provide an apparatus in which the newly cored shaft is returned substantially to the starting point whereby an oper-

ator can readily exchange it for a shaft with full rolls requiring labels.

It is a further very important object of the invention to provide a labeling machine in which the cells for individual stacks of labels are so organized as to minimize the clearance between labels of successive stacks thereby substantially completely covering each roll with its respective label.

Other objects of the invention relate to a novel and improved labeling device in which each roll is mechanically rotated for the application of the label thereto, thereby withdrawing the respective labels from their guides and ensuring the application of a label to each roll; the provision of automatic electrical controls for the apparatus; the provision of novel and improved means for stripping the labeled rolls from the full shaft; the provision of novel and improved means for supporting the respective shafts and for freeing an end of each during the stripping and recoresing operations; and the provision of novel and improved cells for the labels with electrically controlled feeding means for maintaining fresh labels positioned at the tops of the various cells.

In the drawings:

Figure 1 is a side elevation of a machine embodying this invention.

Figure 2 is a plan view thereof.

Figure 3 is an end elevation thereof.

Figure 4 is a detail view in transverse section through the apparatus, showing a series of label cells across which is moving a set of rolls requiring labels.

Figure 5 is an enlarged detail view through a label cell, in longitudinal section.

Figure 6 is a bottom plan view of the cell shown in Figure 5.

Figure 7 is a fragmentary detail in longitudinal section of an intermediate label cell.

Figure 8 is a detail view of a device for applying adhesives to the ends of the labels.

Figure 9 is a diagrammatic perspective of the entire apparatus illustrating the operation of its component parts at the various positions occupied by the respective core shafts in their movement through the apparatus.

Figure 10 is a diagrammatic detail in elevation of the paster.

Like parts are identified by the same reference characters throughout the several views.

5 For the purposes of convenient illustration I have shown a machine for handling fewer labels than would ordinarily be handled in actual practice. It is to be understood that machines embodying this invention may be made in any practical capacity by merely increasing the dimensions of the parts and the number of labeling cells.

General organization and conveyor system

15 The general organization of the machine is very simple. The frame 10, best illustrated in Figures 1, 2 and 3, supports cross shafts 11, 12, 13, and 14. Each of these, except shaft 12, carries two sprockets 15 and 16 at 20 that side of the machine which is closest the observer in Figure 1. Each has a single sprocket 17 at the remote side of the machine. These sprockets carry conveyor chains 18, 19 and 20 respectively.

25 Between sprocket shafts 12 and 13 is a shaft 22 supported by an arm 23 and carrying sprockets 24 and 25 for chains 18 and 19. Chain 20, in passing between sprocket shafts 12 and 13, passes around the back side of a 30 mutilated sprocket wheel 27, as clearly shown in Figures 1 and 3. Sprocket 27 is mounted on a cross shaft 28 having spring centered bearings at its ends, such as that shown at 29 in Figure 1.

35 The three chains 18, 19 and 20 together constitute conveying mechanism for the several core shafts or mandrels. At corresponding points the chains carry brackets 30, 31 and 32 which vary in construction according 40 to their function. A bracket 30 constitutes a head stock within which is yieldably mounted a spring pressed chuck 33, driven by a shaft 34, carrying a pinion 35. Bracket 31 is an open ended fork, as best shown at 45 the left of Figure 9. Bracket 32 comprises a tail stock likewise provided with a spring pressed retractible chuck 37 having spindle 38 headed at 39.

50 Each core shaft or mandrel 40 is placed in the machine by an operator standing at the left of the machine as viewed in Figures 1 and 2. In Figure 2 the head stock 30, tail stock 32 and intermediate bracket 31 are shown open to receive a mandrel carrying full rolls requiring labels. The reduced end portion 41 of the mandrel is first inserted in the tail stock chuck 37. The fulcrum portion 42 of the mandrel is then inserted in the 55 forked fulcrum bracket 31 of the chain 19, chuck 33 being retracted in the meantime by means of pinion 35 which is grasped manually like a hand wheel for the purpose. When the mandrel is in position, the pinion 60 35 is released and chuck 33, under pressure

of its spring, engages the squared end 43 of the mandrel.

As the several chains 18, 19 and 20 operate, they carry with them the mandrels or core shafts mounted in their respective brackets. Between the sprockets mounted on cross shafts 11 and 12 the labeling operation occurs as will hereinafter be more fully described. Immediately after the labeling of the rolls on any given mandrel, the head 39 of its tail stock chuck is engaged by a cam track 45 whereby the chuck is retracted, as shown in Figure 3 and the end of the mandrel 40 is left unsupported.

Immediately thereafter sprocket 27 causes chain 20 to take a different course from that taken by chains 18 and 19 and the withdrawal of tail stock bracket 32 on the new course of chain 20 completely exposes the end of the core shaft or mandrel which is now supported entirely by chains 18 and 19, the latter being provided with a guide 46 for increased rigidity of support.

At this point in the operation of the machine the automatic roll removing mechanism hereinafter to be described commences to operate to push all of the labeled rolls from the mandrel. The movement of the mandrel continues during this stripping operation and after it moves downwardly about sprockets 24 and 25 a second operator may reload the mandrel with cores 47 (see Figures 2 and 9).

As the tail stock brackets 32 pass about the mutilated sprocket 27 they are received in 100 the relieved portions thereof. The spring mounting of the bearing of shaft 28 takes up the slack occasioned by the straightening of the chain 20 as its brackets 32 enter the cut away portions of the sprocket.

As the chain 20 again approaches a position of alignment with chains 18 and 19 a second cam guide 48, similar to cam guide 45, picks up the headed end 39 of the tail stock chuck and retracts it in order that the end portion 41 of the mandrel 40 may become aligned with the chuck to be re-engaged thereby as the head 39 passes from the cam to the position shown at the bottom of Figure 3.

From this point a re-cored mandrel proceeds to a position where it may be removed from the machine and inserted by the operator in the re-winder as above described.

The label cells

The label cell block 50 is mounted on the sub-frame members 51 which extend transversely of the main frame at an intermediate point therein. In the cell block is a stack of labels 52 for each of the fully wound rolls 53 requiring labeling. Guide means are provided for the several stacks of labels and there is also an electrically controlled feeding mechanism for maintaining the labels of 130

each stack in operative relation to the rolls carried by the mandrel 40, regardless of the number of labels remaining in the stack.

Alternate label cells are specifically different from each other, as shown at the right hand side of Figure 4 which is taken in a somewhat different plane from the section in which the left hand side of the view appears. (See also Figures 5 and 7.)

10 The stacks of labels 52 are supported on platforms 55 which are vertically reciprocable between vary thin partition plates 56. These plates do not extend to the tops of the several stacks, but terminate in spaced relation to the top of each stack, as shown in Figure 4.

The platforms 55 are carried by springs 57 from cross head guides 58 having tubular supports 59. Each tubular support is provided 20 with a bearing sleeve 60 for an elevating screw 61 journaled in a socket 62 in the bottom of the respective cell. The top of each bearing socket 62 supports a worm wheel 63 connected with screw 61 and driven by a 25 worm 64. The pins 65, carried by handles 66, pivoted to the tubular support 59, are pressed by spring 67 through openings in the tubular support 59 and the sleeve 60 into operative engagement with the threads of screw 30 61 to constitute the equivalent of a nut for releasably receiving motion from the elevating screw 61. When it is desired to refill any given label cell, the handles 66 are manipulated against the compression of the 35 spring 67 to release the pins 65 from screw 61 and thereby, to free the cross head 58 and false bottom 55 for downward movement so that a new stack of labels may be placed on the false bottom between the guide partitions 56.

40 The feed of worm 64, worm wheel 63 and screw 61 is intermittent. An eccentric 70 on conveyor chain cross shaft 11 is provided with an eccentric strap 71 connected by rod 45 72 with a rocker arm 73 on rock shaft 74 which passes through the several label cells immediately behind the worms 64.

Directly connected to turn with each worm is a gear 75 meshing with a gear 76 which 50 is free on shaft 74 and is connected to turn with a ratchet wheel 77. Rigidly connected with shaft 74 within each cell is a ratchet arm 78 having a pawl 79 constituting an armature for electro-magnet 80. This pawl is 55 arranged to interact with the teeth of ratchet 77 except when the electro-magnet is energized and on such occasions it is lifted out of a position for operative engagement with the ratchet. The construction is clearly 60 shown in Figure 5.

It will be noted that the guides 56 not only terminate below the top of each label stack as above noted, but are relieved at their ends, as shown in Figure 5. In order to 65 guide the labels of each stack at the top of

the stack I have provided at one end of the stack arms 82 which are pivoted and subject to the tension of springs 83 which tend to hold guide portions 84 of these arms at the level of the top of the stack, subject, however, to yielding movement when the arms are traversed by toilet rolls. The ends of the labels are guided by pressure plate 85 and the uppermost label is barely engaged by a spring 70 clip 86.

At the back of the stack is a guide 87 for the ends of the labels which is fulcrumed like a bell-crank, as shown in Figure 5, and subject to the tension of spring 88. Alternate stacks of labels are engaged at the rear end 80 by a yoke-shaped guide 90 which includes a flat plate resting across the top of the stack of labels in spaced relation to the end thereof, and thin sheet metal arms 91 which register with the partitions 56 between the respective cells and hence fit between adjacent stacks of labels. These arms are fulcrumed on bolt 92 and connected with a channel 93 which serves as a seat for a compression spring 94 guided by a tie-rod 95. This rod 90 carries a switch contact 96 coacting with a stationary switch contact 97, the respective contacts being connected in series with a source of current 98 and the electro-magnet 95 85 above described.

The guides 90 are not used on every cell because such use would involve duplication of the thickness of arms 91 and this would space the stacks of labels to an undesirable degree. It will be understood that the rolls 100 53 contact at their ends, being re-wound from a single longitudinally slitted web. To the extent to which the stacks of labels are spaced apart the ends of these rolls will be exposed.

The stacks of labels intermediate guides 90 are laterally confined by arms 91 of such guides at each side. In order that each such stack may be governed independently as to feed, a special finger is used as shown at 100 105 in Figure 7. This finger is fulcrumed at 101 110 and carries a contact 96' coacting with a contact 97', the two contacts being electrically wired to perform the functions of contacts 96 and 97 in Figure 5.

The arrangement is such that during the 115 operation of the machine rock shaft 74 is continuously oscillated to and fro. At each oscillation the pawl 79, carried by ratchet arm 78, will act on the ratchet 77 to operate the gear train which turns each feed screw 61, unless it so happens that the labels of a particular cell have reached the maximum desired level in that cell. In that case the pressure of the labels will act on the guide 90 120 in the Figure 5 cell construction or upon the guide 100 in the Figure 7 cell construction to close the contact which energizes magnet 80, and thereupon the pawl 79 will be lifted 125 out of operative position and will no longer act to elevate the labels of its cell until enough 130

labels have been used to relieve the pressure on the guide or spring finger and thereby to permit the contacts to open.

Before describing the manner in which the labels are applied to the roll, I shall now describe the pasting mechanism which renders the top label of each stack adhesive.

Pasting mechanism

10 The paste applying bars 105 and 106 are carried by rock shafts 107 and 108 respectively, which are mounted on racks 109 and 110, provided with rack teeth 111, and arranged for reciprocation in vertical guides 112. The 15 pasting bars normally hang by gravity at substantially the angle indicated in Figure 1 at the left but each of the rock shafts 107 and 108 is provided with a finger 113 which, in the lowermost position of the respective 20 rock shafts, interacts with a stationary stop 114 to oscillate rock shaft 108 to a position in which the bar 106 will be vertical and its lower margin will be directed flat upon one 25 end or the other of the uppermost label of each stack. Additional stops 115 are positioned above the path of travel of arms 113, as shown in Figure 2 and Figure 10, so that during the upward movement of the respective 30 racks 109 and 110 arms 113 will be engaged by stops 115 to oscillate the respective rock shafts 107 and 108 counter-clockwise, as viewed in Figure 10, to bring the paste carrying lower edges of the paster bars 105 and 35 106 into contact with the paste carried by rolls 116 which operate in paste receptacles 117 and are chain driven from shaft 22.

In order to provide for the vertical reciprocation of the racks 109 and 110, I employ segments 118, meshing with the respective 40 racks and mounted on rock shafts 119 supported from the upright guides 112. An arm 120, connected to each rock shaft, hangs in the path of movement of mandrels 40 so that the passage of each mandrel will lift the 45 paster out of the path of the rolls carried by the mandrel, bringing its pasting margins into contact with the paste peripherally carried by roll 116, and allow the gravity return of the paster into engagement with the next successive label after the roll has passed.

It will be noted from Figures 7 and 8 that the paste bearing margins of the paster bars 106 are notched at 122 to clear the fingers 100 of alternate label cells. In the type of cell shown in Figure 5 the paste bearing margin of paste bar 106 engages the label between the top plate of guide 90 and the end of the label and no notch is required.

Engagement of the roll with the label

As the conveyor chains carry the respective mandrels 40 along the top of the machine, the pinions 35, connected with driving chucks 65 33 in the head stock brackets 30, will mesh

with the stationary rack 125 (see Figures 1, 3 and 4). It is expressly to be noted that the pinions 35 are smaller in diameter than the rolls 53 which require labels. Because of this fact, the rolls 53 are rotated somewhat more rapidly than would be the case if they were merely contacting at their peripheries with a stationary surface.

As each roll clears the clip 86 and rolls onto the adherent end of its respective label, from which the paster bar has been removed by the advance of the mandrel, the label will stick to the outer periphery of the roll and hence will free itself from the clip 86. If the mere rolling contact of the respective rolls with the respective labels were relied upon to wind the labels upon the rolls, the result would by no means be certain since the rolls might not have uniform pressure engagement with their respective labels. In the arrangement disclosed, however, the relatively rapid rotation of the rolls not only positively winds each label upon its roll but also withdraws the remote end of each label from beneath its contact guide comprising, in the Figure 5 construction, the guide 90, and in the type of cell shown in Figure 7, the contact finger 100. Thus, before the roll reaches the guide, the label has been completely wound upon it and has been sealed at the point of overlap by the pressure engagement of the roll with the stack of labels therebeneath.

Removal of labeled rolls from the mandrel

As the tail stock frees the end of mandrel 40 the labeled rolls carried by that mandrel become subject to the automatic operation of a device which slides the whole series of rolls from the mandrel.

Threaded upon a feed screw 130 is a forked arm 131. The feed screw is driven forwardly and reversely by means of motor 132 and gearing at 133.

As a mandrel 40 approaches the position for discharge of its labeled rolls, it enters the forked end of arm 131 which has been left approximately in the position shown in Figure 1 by friction between the screw and the arm during the clockwise rotation of the screw, (as viewed in Figure 1) which has restored the arm to its initial position.

As the mandrel continues to move, the fork 131 commences to oscillate upon the screw 130 in a clockwise direction, as viewed in Figure 1, and the finger 135 carried thereby engages switch 136 thereby initiating the operation of motor 132 in a counter-clockwise direction. This causes the forked arm 131 to feed along the mandrel during the continued movement of the mandrel and thereby to force all of the labeled rolls from the free end of the mandrel. At the conclusion of this operation, the forked arm will have swung and traveled to a position where it will engage the stop switch 137, thereby bringing

the motor to rest. As the mandrel is still moving on the conveyor chain, however, the arm 131 will continue to oscillate upon the screw until it clears the mandrel, at which time it will engage the reversing switch 138 to cause a reverse operation of motor 132 and screw 130 which will return the forked arm first to its original angular position and then, during the continued operation of the screw, 10 to its original starting point at the side of the machine. Here the finger 135 will strike the stop switch 139 thereby bringing the apparatus to rest.

15 *Re-coring the mandrel shaft*

Since the re-coring of the mandrel shaft is a simple operation requiring no skill and involving no danger, it can readily be performed by hand by inexperienced operators 20 who will simply slip cores 47 onto the mandrels as soon as the labeled rolls have been stripped therefrom as above described. The tail stock end of the mandrel is still free, as shown at the right in Figure 9.

25 *Driving connections and summary of operations*

The main drive for the machine is derived from a motor 150 and reduction gearing at 30 151 and 152 to shaft 153 which carries a pinion 154 meshing with a gear 155 on the cross shaft 14 which carries sprockets 15, 16 and 17 for the respective conveyor chains.

Motor 150 is controlled by a pair of three-way switches 156 and 157 of which the former is automatically operated and comprises a motor stopping switch, while the latter is manually operated and is used primarily as a starting switch.

40 As a mandrel, supported by brackets 30, 31 and 32 on the several conveyor chains, approaches the operator's station pinion 35 encounters the actuator 158 for switch 156 and thereby cuts off the current supply to motor 45 150. The parts will continue to operate to advance the cored mandrel for a short distance.

The operator now uses pinion 35 as a handle to retract the driving chuck 33 from the mandrel and is thereby enabled to lift the cored mandrel from the head stock bracket 30, the fulcrum bracket 31 and the tail stock bracket 32. He now substitutes for the withdrawn cored shaft a mandrel upon which the cores 55 are filled with toilet rolls requiring labels and having positioned this mandrel on the several brackets of the three conveyor chains, he sets the machine in operation by means of a switch 157.

50 The initial movement of the mandrel will bring the head stock driving pinion 35 into engagement with rack 125 so that the rolls carried by the mandrel will be in rotation when they roll onto the labels exposed in the label cell block 50. The ends of these labels

will adhere to the several rolls and the mechanically driven rotation of the rolls will not only draw the labels from beneath the retaining guides at their far ends but will wind the labels on the rolls and ensure their overlap under sufficient compression to seal each label. As the mandrels approach the labels they lift the arms 120, as above described, and thereby cause each pasting bar successively to move upwardly out of the path of the rolls, acquiring a fresh charge of adhesive, and subsequently return to the next successive label.

Immediately after the mandrel passes clear of the label cells, one end is freed due to the engagement of the head 39 of the tail stock chuck 37 in retracting cam 45. This withdraws the chuck 37 from the mandrel and immediately the chain 20, bearing the tail stock bracket 32, assumes a course entirely different from that of chains 18 and 19. The passage of chain 20 around the back side of sprocket 27 leaves the end of mandrel 40 entirely clear, as best shown in the diagrammatic view comprising Figure 9.

As the mandrel movement continues, the mandrel becomes engaged in the forked end of arm 131 which is thereby set in motion and its separate driving motor 132 operates screw 130 to cause a complete traverse of arm 131 across the machine and back. In its forward movement, the fork strips the labeled rolls from the mandrel, and its return movement leaves the fork in position for engagement with the next mandrel.

While the end of the mandrel is still clear in passing about the back of the machine, the mandrel is re-cored by simply slipping cores 47 onto the exposed end thereof. Immediately thereafter the head 39 of tail stock chuck 37 is again picked up by a retracting cam 48 and chain 20 is restored to alignment with chains 18 and 19, and tail stock chuck 37 is brought into registry with mandrel 40 while the chuck is thus retracted. When cam 48 is cleared and the chuck is released, it again engages the end of the mandrel and the mandrel remains supported by all three conveyor chains until it is again withdrawn at the operator's station as above described.

I claim:

1. In a device of the character described, a mandrel shaft conveyor comprising traveling means for supporting a mandrel shaft at two spaced points adjacent one end thereof while leaving the other end free.

2. In a device of the character described, the combination with conveyor means having head stock and tail stock brackets provided with mandrel chucks and an intermediate fulcrum bracket adjacent one of said first mentioned brackets, of means for retracting the chuck remote from said fulcrum bracket whereby to release the corresponding end of a mandrel engaged thereby.

3. In a device of the character described, the combination with conveyor means having head stock and tail stock brackets provided with mandrel chucks and an intermediate fulcrum bracket adjacent one of said first mentioned brackets, of means for retracting the chuck remote from said fulcrum bracket whereby to release the corresponding end of a mandrel engaged thereby, and means for withdrawing the bracket from which said mandrel end was released by the retraction of said chuck, whereby to expose the free end of the mandrel. 70
4. In a device of the character described, the combination with a set of conveyors provided with head stock, tail stock and fulcrum brackets, said head stock and tail stock brackets having mandrel engaging chucks, of guide means for said conveyors differing as to path, whereby one of said brackets is caused to follow at one point in the movement of said conveyors a wholly different path from the path followed by the other brackets, and means for retracting out of engagement with a mandrel carried by said brackets the chuck of the bracket guided to follow a different path from that of the other bracket. 80
5. In a device of the character described, the combination of a set of three conveyors, brackets carried by each in generally corresponding paths, means for retracting one of said brackets from a predetermined portion of said path, and a retractible chuck carried by the retractible bracket and provided with means for withdrawing said chuck from an article supported by the other two brackets before retracting the retractible bracket from said path. 85
6. In a labeling machine a mandrel conveyor system comprising a plurality of chains provided with mandrel brackets, a sprocket about the back side of which one of said chains passes in a course different from that of another of said chains, a retractible chuck carried by the bracket of the chain passing about said sprocket, said chuck being provided with a head, and cam means disposed adjacent the path of said head and adapted automatically to act thereon to retract said chuck from a mandrel engaged thereby during the change of direction of the bracket carrying said chuck whereby to free the end of such mandrel. 100
7. In a labeling machine the combination of a head stock conveyor chain, a tail stock conveyor chain and a fulcrum bracket conveyor chain, guides providing corresponding paths for two of said chains, a guide for the third chain providing a path corresponding to the path of said first two chains throughout their course except during a predetermined interval at which the path of said third chain is divergent from the path of said first mentioned chain, chucks carried by said third chain and one of said first mentioned chains, a head upon the chuck of said third chain, and cam means engageable with said head and adapted for the retraction thereof at the point of divergence of said third chain from the path of said first chain and at the point of convergence of said third chain with the path of said first two chains. 110
8. A labeling machine comprising a frame provided with cross shafts, a pair of sprockets adjacent one end of a cross shaft, a third sprocket remote from said pair of sprockets on said cross shaft, sprockets upon the other cross shafts aligned with the sprockets of said first mentioned cross shaft, first, second and third chains operating over the respective sprockets in circuitous paths which are identical in the case of the first and second chains and different in the case of the third chain, chuck brackets and fulcrum brackets carried by the first two chains, a chuck bracket carried by the third chain normally in registry with the brackets of the first two chains, means for retracting the chuck in the bracket of the third chain at the time of path divergence of said third chain, and means for retracting the chuck of said third chain at the time of path convergence of the third chain. 120
9. In a labeling machine, the combination with means for supporting a plurality of stacks of labels and a conveyor provided with means for engaging the ends of a mandrel shaft bearing rolls to be labeled, of means guiding said conveyor for the movement of the roll bearing mandrel across said label stacks, and means for freeing one end of said mandrel from said conveyor while maintaining the other end of said mandrels supported in said conveyor. 130
10. In a labeling machine, the combination with guide means for a plurality of stacks of labels and conveyor means operating across said guide means, of mandrel chucks carried by said conveyor means, an auxiliary support carried by said conveyor means and disposed to be adjacent one end of a mandrel shaft mounted thereon, means for rotating one of said chucks during the traverse of the mandrel shaft across stacks of labels carried by said guide means, and means for retracting one of said chucks to free an end of a mandrel shaft engaged thereby. 140
11. In a labeling device the combination with guide means for stacks of labels and a conveyor provided with mandrel chucks and adapted to cause rolls supported by a mandrel to traverse labels supported by said guide means, of a driving device on one of said chucks, and means for positively rotating said device during the movement of said chuck past the label guides, said drive means being adapted to rotate said chuck at a rate greater than the rate of rotation of a roll on said mandrel in rolling upon the surface of a label. 150

12. In a labeling device the combination with means for supporting a stack of labels and a conveyor provided with a mounting for the rotatable support of an article to be labeled, of a driving pinion on said support of less diameter than the article to be labeled, and a rack disposed in the path of said pinion and adapted to cause rotation of said support during conveyor movement.
13. In a labeling machine the combination with a support for a stack of labels of a conveyor for supporting a mandrel in a position to traverse said labels, said conveyor comprising a pair of closely spaced brackets adapted to receive one end of a mandrel and to support it independently of any support at the other end, driving means operatively connected to drive the end of a mandrel so supported, and means for actuating said driving means while said mandrel traverses said stack of labels.
14. In a labeling machine the combination with conveyor means mounted for circuitous movement and provided with closely spaced mandrel brackets both engageable with the same end of a mandrel and adapted throughout at least a portion of the conveyor circuit to support the mandrel independently of any support at the other end, of a label cell block in the path of movement of the mandrel adapted to support a stack of labels for application to an article carried by the mandrel, of a label rotating chuck connected with one of said brackets and provided with means for rotating it at a rate exceeding the peripheral travel of such an article across said label cell block, and means for releasing a mandrel from said chuck and brackets whereby it may be released at a given point in the circuitous travel of said conveyor means.
15. In a labeling machine the combination with conveyor means organized for circuitous travel and adapted to carry a mandrel throughout its range of movement from a given station to the same station, of brackets on said conveyor means adapted for detachable engagement with a mandrel, two such brackets being engageable with a mandrel adjacent one end thereof and one such bracket being engageable with a mandrel adjacent the other end thereof, means for disengaging said last mentioned bracket from the mandrel whereby to leave the mandrel supported by said first mentioned pair of brackets, means for causing the disengaged bracket to follow a path different from the end of the mandrel previously disengaged by it, whereby to leave said mandrel end free, and means enclosed between said station and said predetermined point in the travel of said conveyor means for labeling articles carried by the mandrel, said articles being freely removable from the mandrel over the free end thereof subsequent to the labeling operation.
16. Labeling apparatus comprising conveyor means for opposite ends of a mandrel, conveyor guides for the respective means defining paths which are generally identical but which deviate at one point in the conveyor travel, brackets carried by the respective conveyor means and normally engaged with both ends of the mandrel, means for freeing one end of the mandrel from one of the brackets at the point where the conveyor paths deviate, the other conveyor means being adapted for the sole support of the mandrel when its end is freed from said bracket, and a labeling device in the path of travel of the mandrel as it approaches the point where its end is so freed.
17. Labeling apparatus comprising conveyor means for opposite ends of a mandrel, conveyor guides for the respective means defining paths which are generally identical but which deviate at one point in the conveyor travel, brackets carried by the respective conveyor means and normally engaged with both ends of the mandrel, means for freeing one end of the mandrel from one of the brackets at the point where the conveyor paths deviate, the other conveyor means being adapted for the sole support of the mandrel when its end is freed from said bracket, and a labeling device in the path of travel of the mandrel as it approaches the point where its end is so freed, including means for positively rotating the mandrel as it traverses said device.
18. A labeling device comprising a set of three conveyor chains, two of which are close together and the third of which is relatively remote, means defining circuitous paths for said chains corresponding except at a predetermined point in the circuit at which the path of the remote chain deviates from the path of the two chains which are close to each other, brackets mounted on the respective chains for a mandrel, the bracket of the intermediate chain being slotted and the bracket of the outside chains being provided with yieldable mandrel chucks, a head on the chuck carried by said relatively remote chain and a cam guide adapted to retract said head and thereby to free said chuck from the end of a mandrel as the bracket of said remote chain approaches the point of deviation, and a labeling device in the path of the mandrel approaching said point.
19. A labeling device comprising a set of three conveyor chains, two of which are close together and the third of which is relatively remote, means defining circuitous paths for said chains corresponding except at a predetermined point in the circuit at which the path of the remote chain deviates from the path of the two chains which are close to each other, brackets mounted on the respective chains for a mandrel, the bracket of the intermediate chain being slotted and the bracket

- of the outside chains being provided with yieldable mandrel chucks, a head on the chuck carried by said relatively remote chain and a cam guide adapted to retract said head and thereby to free said chuck from the end 5 of a mandrel as the bracket of said remote chain approaches the point of deviation, and a labeling device in the path of the mandrel approaching said point, together with means for re-engaging the retractive chuck with said mandrel as said chains resume their travel upon like paths, whereby the mandrel may be carried by the chains to the point of 10 beginning.
- 15 20. In a labeling device the combination with a label cell block, of a mandrel conveyor provided with bearings for mandrel rotation and a chuck rotatable in one of said bearings and engageable with a mandrel, a pinion connected with said chuck for the rotation of a mandrel, said pinion being of less diameter than an article on the mandrel to be labeled, and a stationary rack adapted to be engaged by said pinion during the transverse of said 20 cell block by the mandrel, whereby to rotate the pinion and thereby to turn an article on the mandrel at a peripheral speed exceeding the rate of travel of the mandrel across the cell block.
- 25 30. 21. In a labeling device the combination with means for guiding a stack of labels for movement to a predetermined point of delivery, means for rolling an article to be labeled across the stack of labels at the delivery point, a limiting member holding one end portion of the label of said stack adjacent the delivery point, and means for rotating an article traversing said stack at a rate exceeding its rolling speed, whereby to draw 35 from beneath said limiting member the label applied to said article.
- 40 45. 22. In a labeling device the combination with a support for a stack of labels, and means for moving across the face of the stack an article to be labeled, of a pasting transfer member provided with an elevated supply, and connections for operating said member upwardly from said label stack to said supply in the course of advance of said means, where- 50 by to clear the article to be labeled and simultaneously to obtain paste at said source for the next successive label of the stack.
- 55 60. 23. A labeling device comprising guide means for a stack of labels, means for maintaining said stack under pressure toward a point of label delivery, means for conveying an article to be labeled across the stack in contact with the foremost label at the point of delivery, a paste transfer member normally 65 resting on the foremost label of the stack and a paste supply roll spaced from the stack, and means operative in accordance with the advance of the member to be labeled for moving said member from the label to the roll, whereby to clear the article and require a fresh sup- 70

ply of adhesive for the next successive label, the previously treated label being adapted to adhere to the article traversing it.

24. In a labeling device, the combination with a label guide and a paste reservoir, of a conveyor adapted to carry an article between said guide and reservoir for labeling, a paster normally resting on the surface of a label carried by said guide and provided with actuating connections adapted to elevate it to the 75 reservoir upon the approach of an article, and means for positively rotating said article during its traverse of said guide, whereby to pick up a previously pasted label and roll it upon the article. 80

25. A labeling machine comprising the combination with a label guide and a paste reservoir spaced therefrom, of a slide member reciprocable to and from the label guide in the direction of the reservoir, a rock shaft 85 carried thereby, a paster mounted on the rock shaft, an arm projecting laterally from the rock shaft, stops engageable by said arm and determinative of the position of the paster, and actuating connections for said slide including an arm depending in the path of movement of an article requiring a label, together with a conveyor for advancing such an article across the label guide. 90

26. In a labeling device the combination with conveyor means having brackets engageable with the ends of mandrels for supporting freely the opposite ends of such mandrels, of means for stripping articles from a mandrel so supported, said means comprising a stripping member movable with the mandrel in the course of conveyor movement and provided with actuating connections for impelling it longitudinally of the mandrel, whereby to deliver from the free end thereof articles carried thereby. 95 100 105

27. In a device of the character described, the combination with a mandrel support engageable with one end of the mandrel and adapted to leave the other end free, of means for stripping articles from the mandrel comprising a mechanically driven finger guided for travel longitudinally of the mandrel in end engagement with articles mounted thereon. 110 115

28. In a device of the character described, the combination with a mandrel support engageable with one end of the mandrel and adapted to leave the other end free, of means for stripping articles from the mandrel comprising a mechanically driven finger guided for travel longitudinally of the mandrel in end engagement with articles mounted thereon, together with conveyor means for transportation of a mandrel so supported and an automatic control for said stripper provided with regulator means operative in accordance with the movement of the mandrel. 120 125

29. In a device of the character described, the combination with a mandrel and sup- 130

porting means engageable with one end thereof to leave the other end free, of a stripping device for said mandrel comprising a finger mounted for travel longitudinally of the mandrel, and means for controlling the movement of the finger.

30. In a device of the character described, the combination with a mandrel and supporting means engageable with one end thereof to leave the other end free, of a stripping device for said mandrel comprising a finger mounted for travel longitudinally of the mandrel, and means for controlling the movement of the finger, said mandrel support being mounted on a conveyor and said finger being mounted to accommodate the conveyor movement during its stripping movement.

31. In a device of the character described, the combination with a support for one end of 20 a mandrel adapted to carry the other end free, of a device for stripping articles from the mandrel comprising a fork mounted for travel longitudinally of the mandrel, a mechanical actuating device for the fork, and 25 means for automatically controlling the travel of said fork toward the free end of the mandrel and return.

32. In a device of the character described, the combination with a support for one end 30 of a mandrel adapted to carry the other end free, of a device for stripping articles from the mandrel comprising a fork mounted for travel longitudinally of the mandrel, a mechanical actuating device for the fork, and 35 means for automatically controlling the travel of said fork toward the free end of the mandrel and return, the actuating connections for said fork comprising a motor driven screw upon which said fork is threaded, and 40 said mandrel support being mounted on a conveyor for movement beneath the screw, accommodated by an angular movement of the fork in the course of its longitudinal movement.

45. 33. In a device of the character described, the combination with a support for one end of a mandrel adapted to carry the other end free, of a device for stripping articles from the mandrel comprising a fork mounted for 50 travel longitudinally of the mandrel, a mechanical actuating device for the fork, and means for automatically controlling the travel of said fork toward the free end of the mandrel and return, the actuating connections for said fork comprising a motor driven screw upon which said fork is threaded, and 55 said mandrel support being mounted on a conveyor for movement beneath the screw, accommodated by an angular movement of 60 the fork in the course of its longitudinal movement, said control means comprising a series of switches, and a switch actuating means connected with the fork and arranged to engage the proper switches for the control of said screw in accordance with the

angular and longitudinal position of the fork.

34. A labeling machine comprising the combination with a conveyor arranged for circuitous travel, and mandrel supporting means carried by the conveyor and adapted during at least a portion of said travel to leave free one end of a mandrel carried thereby, of means operative during the travel of a mandrel across the aforesaid portion of the conveyor path for mechanically stripping from the mandrel articles carried thereby, and labeling means disposed in the path of movement of said articles toward a stripping device and comprising label guides, label pasting means, label feeding means, and means for wrapping the label upon each article carried by such a mandrel.

35. In a labeling machine a device for stripping labeled rolls from a supporting 85 mandrel, said device comprising a feed screw, a mandrel conveyor adapted to expose one end of the mandrel in passing the feed screw and a stripping member threaded upon said feed screw with which said mandrel is engageable in the course of movement of said conveyor, said stripping member being adapted to take its angular position upon said feed screw from the mandrel during an operation of said screw.

36. In a labeling machine a device for stripping labeled rolls from a supporting mandrel, said device comprising a feed screw, a mandrel conveyor adapted to expose one end of the mandrel in passing the feed screw and a stripping member threaded upon said feed screw with which said mandrel is engageable in the course of movement of said conveyor, said stripping member being adapted to take its angular position upon 100 said feed screw from the mandrel during an operation of said screw, together with reversible operating means for the feed screw, and control devices engageable by said stripping member in the course of its angular and linear movement upon said screw for initiating, stopping, reversing, and again stopping said connections.

37. A device for stripping articles from a mandrel movable on a conveyor, said device comprising a screw adjacent the path of mandrel travel, a stripping member threaded to said screw and movable longitudinally thereof from a normally retracted position to an advanced position and back, means carried by said member whereby it takes its angular position on the screw from the mandrel during engagement therewith, whereby to vary the angular position of said member during the advance of the mandrel on its conveyor, and means for reversing the operation of the screw to restore said member to its original position, the thread of the screw being designed to restore said member to 115 120 125 130

ward its original angular position in the course of its reversed rotation.

38. A device of the character described comprising a screw provided with driving connections, a stripping fork provided with a threaded connection to the screw to be operated thereby, said stripping fork being mounted for angular movement, a conveyor provided with means engageable with the fork for its angular adjustment, and a control member for the actuating connections of said screw positioned in the path of initial angular movement of said fork to be operated thereby for the initiation of screw movement when said fork is engaged by said conveyor means.
